UNITED STATES PATENT OFFICE.

TOUSSAINT TRUDEAU, OF OTTAWA, CANADA.

DESIGN FOR A GAS-GLOBE GALLERY.

Specification forming part of Design No. 7,931, dated December 15, 1874; application filed May 20, 1874.
[Term of Patent 14 years.]

To all whom it may concern:

Be it known that I, TOUSSAINT TRUDEAU, of the city of Ottawa, in the Province of Ontario, in the Dominion of Canada, have invented a Design for a Gas-Globe Gallery, of which the following is a specification:

The nature of my design represented in the accompanying drawing, to which reference is made, is for a gallery to sustain a gas-globe, more especially the gas-globe which I have invented, and for which I have obtained a reissue Patent No. 4,633, November 7, 1871. This globe is sustained on a gallery with straight or slightly-curved arms, as shown in the drawings attached to the specification of the patent above named. I have found in practice that a gallery of this form placed on the burner unfavorably affects the globe which it sustains. It reduces the apparent height of the globe, and gives it an isolated character, as if disconnected with the gasalier, and, in cases of ornamental gas-pendants, detracts from the general appearance.

The gallery shown in the drawing attached to my patent was invented with a view to its utility.

The gallery which I have now designed forms an ornamental auxiliary to the gas apparatus.

The essence of my design is to give vertical depth to the gallery, and to cluster material near the stem of the burner, so as to create a group of ornament under the immediate center of the globe.

Figures 1 and 2 of the accompanying drawing represent my gallery.

A represents a gas pillar and burner. B represents center-piece of gallery. C C C represent the arms. D D represent a globe.

What I claim as my invention is—

The design for a gas-globe holder, as described, and shown in the accompanying drawings.

T. TRUDEAU.
